FIG. 1.

FIG. 2.

FIG. 3.

FIG. 4.

FIG. 5.

FIG. 6.

Inventor
M. T. Prillaman

Say Attorney

UNITED STATES PATENT OFFICE.

MAURIE T. PRILLAMAN, OF BLUEFIELD, WEST VIRGINIA.

RAILWAY RAIL JOINT.

Application filed June 4, 1925. Serial No. 34,983.

To all whom it may concern:

Be it known that I, MAURIE T. PRILLAMAN, a citizen of the United States, residing at Bluefield, in the county of Mercer and State of West Virginia, have invented certain new and useful Improvements in Railway Rail Joints; and I do hereby declare the following to be a full, clear, and exact description of the invention, such as will enable others skilled in the art to which it appertains to make and use the same.

This invention has for one of its objects the provision of a rail joint which shall be exceedingly simple and durable and through the medium of which the meeting ends of railway rails may be firmly connected without the aid of fish plates or angle bars.

The foregoing and other objects are attained by the construction, combination and arrangement of parts hereinafter fully described and claimed, and illustrated in the accompanying drawing, wherein:

Figure 1 is a view in side elevation of a pair of railway rails connected together by a joint embodying my invention;

Figure 2 is a top plan view of the rails;

Figure 3 is a bottom plan view of the rails;

Figure 4 is a sectional view taken on the vertical plane indicated by the line 4-4 of Figure 1;

Figure 5 is a perspective view of one of the rails, and

Figure 6 is a perspective view of the other rail.

Corresponding and like parts are referred to in the following description, and designated in the several views of the accompanying drawing, by similar reference characters.

In the drawing 1 and 2 designate a pair of railway rails. The rail 1 is provided in its upper side with a groove 3 and the rail 2 in its lower side with a groove 4. The grooves 3 and 4 extend centrally and longitudinally of the rails, and have a depth substantially equal to one-half the corresponding dimension of the rails. The groove 3 opens out through the end and top side of the rail 1, and the groove 4 opens out

through the end and bottom side of the rail 50 2. Below its groove 3 the rail 1 is provided with a centrally arranged and longitudinally extending projection 5, and above its groove 4 the rail 2 is provided with a similar projection 6. The depth of the projections 5 and 6 is approximately equal to one-half the similar dimension of the rails 1 and 2. The top side of the projection 5 is located in the plane of the bottom wall of the groove 3 and the bottom side of this projection is located in the plane of the bottom of the rail 1. The top side of the projection 6 is located in the plane of the top side of the rail 2 and the bottom side of this projection is located in the plane of the top wall of the groove 4. The web of the rail 1 and the projection 6 of the rail 2 are provided with registering openings 8 and 8^a, respectively, for the reception of bolts 10. The web of the rail 2 and the projection 5 of the rail 1 are provided with registering openings 11 and 11^a, respectively, for the reception of bolts 12.

The projection of one rail has a snug fit in the groove of the other rail, and the combined vertical dimension of the projections is equal to the vertical dimension of the rails. In view thereof, and as the bolts passing through one rail pass through the projection of the other, it will be understood that the rails are firmly connected together and that the projection 6 provides the rails with a substantially continuous top side.

What is claimed is:

A pair of railway rails of which one is provided with an upper groove and a lower projection and the other with an upper projection and a lower groove, the projection of one rail snugly fitting in the groove of the other, the top side of one projection being located in the plane 85 of the top sides of the rails and the bottom side of the other projection being located in the plane of the bottom sides of the rails, and bolts passing through the webs of the rails and through the projections. 90 95

In testimony whereof I affix my signature.

MAURIE T. PRILLAMAN.
